UNITED STATES PATENT OFFICE.

WILLIAM F. NIEDRINGHAUS, OF ST. LOUIS, MISSOURI.

VESSEL OF ENAMELED IRON-WARE.

SPECIFICATION forming part of Letters Patent No. 290,597, dated December 18, 1883.

Application filed September 19, 1883. (No model.)

To all whom it may concern:

Be it known that I, WILLIAM F. NIEDRINGHAUS, of St. Louis, Missouri, have made a new and useful Improvement in Vessels of Enamelled Iron-Ware, of which the following is a full, clear, and exact description, reference being had to the annexed drawings, making part of this specification, in which—

Figure 1 is a view in perspective of the improved vessel, and Figs. 2 to 9 details upon an enlarged scale, Fig. 2 being a view in its developed form of that portion of the vessel with which the improvement is immediately connected; Fig. 3, a section on the line 3 3 of Fig. 15; Fig. 4, a side view of the ring or ear; Fig. 5, an edge view of the ring or ear inserted in the perforation in the basin-flange; Fig. 6, a section on the line 6 6 of Fig. 8; Fig. 7, a side view of the ring or ear in position; Fig. 8, a section on the line 8 8 of Fig. 7, and Fig. 9 a section (similar to Fig. 8) of the article after it is enameled.

The same letters of reference denote the same parts.

25 The present invention is an improved mode of constructing and attaching a ring or ear to enameled sheet-iron vessels, such as wash-basins.

The flange *a* of the basin *A* is slit at *a'*, Figs. 30 2, 3. A ring or ear, *B*, Fig. 4, having the eye *b*, open at its neck *b'* and extended at *b'' b''*, is inserted from beneath in the slit *a'*, as in Fig. 5. The flange *a* is then turned to form the bead *a''*, which incloses the extensions *b'' b''*, as shown in Figs. 6, 8, 9, and after the bead is formed the eye *b* projects therefrom, as shown in Figs. 1, 7, 8, 9, directly from the middle of the bead and in the general direction of the

flange *a*. The vessel is then enameled in the customary manner. The enamel serves to close the joint around the neck of the ring or ear, as well as to impart a finish to the article, and, owing to the manner in which the ring or ear is attached, there is no liability, when several of the vessels are nested, as in shipping, of the enamel upon one of the vessels being abraded by the ear upon the adjoining vessel rubbing upon it.

No claim is made herein, broadly, to a ring or ear attached to the vessel in the manner described, this being reserved to my application filed of even date herewith, and officially numbered 106,885. An essential feature of the present invention or improvement is the ring or ear provided with an open neck or eye, *b*, open at the neck, as hereinbefore set forth.

I claim—

1. The combination of the vessel *A* and the ring or ear *B*, said vessel having the bead *a''*, slit, said ring or ear having the open eye *b* and the extensions *b'' b''*, inclosed in said bead, and the vessel being enameled, substantially as described.

2. A sheet-iron vessel having a ring or ear provided with an open neck and projecting through a slit in the beaded edge of said vessel, and being attached thereto by extensions inclosed in the bead, the said vessel being enameled, so that the enamel fills the space in and around the aforesaid open neck, substantially as described.

WM. F. NIEDRINGHAUS.
